CLAIM

The ornamental design for a screen bar clamp lamp, as shown and described.

DESCRIPTION

FIG. 1 is a bottom, front and right side perspective view of a screen bar clamp lamp showing my new design;

FIG. 2 is a top, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is an enlarged view of portion 11 in FIG. 3;

FIG. 12 is an enlarged view of portion 12 in FIG. 5; and,

FIG. 13 is an enlarged view of portion 13 in FIG. 7.

The broken lines in the drawings illustrate portions of the screen bar clamp lamp which form no part of the claimed design.

The labeled broken line portions shown in FIGS. 1, 2, 3, 5, and 7 and the broken lines shown in FIGS. 9-13 are for the purpose of illustrating the boundaries of the enlarged fragments shown in FIGS. 9-13.

The screen bar clamp lamp is shown with symbolic breaks in its length. The appearance of any portion of the article between the break lines forms no part of the claimed design.
